UNITED STATES PATENT OFFICE.

CYRUS W. BALDWIN, OF CHICAGO, ILLINOIS, ASSIGNOR TO WILLIAM E. HALE, OF SAME PLACE.

GAS-ENGINE.

SPECIFICATION forming part of Letters Patent No. 276,748, dated May 1, 1883.

Application filed August 10, 1882. (No model.)

To all whom it may concern:

Be it known that I, CYRUS W. BALDWIN, a citizen of the United States, residing at Chicago, in the county of Cook, State of Illinois, have invented certain new and useful Improvements in Gas-Engines; and I do hereby declare the following to be a full, clear, and exact description of said improvement, sufficient to enable others skilled in the art to which it appertains to practice the same, reference being had to the accompanying drawings, in which—

Figure 1 is a view in longitudinal section through the main or explosion cylinder and through the compression-cylinder pertaining to the invention. Fig. 2 is a view in plan with boiler-casing partly broken away, and Fig. 3 a view in end elevation of the engine and attachments embodying my invention.

The invention has for its object to secure increased efficiency in what are known as "gas-engines," and to permit the same to be started from a distant point without need of first moving the engine by hand. These objects are attained by constructing an apparatus in manner hereinafter set forth.

Referring to the accompanying drawings, in which like parts are designated by like letters of reference, A is the cylinder in which the gaseous mixture is exploded against the trunk-piston B, the movement of which may be imparted by a connecting-rod, b, to a crank-shaft, C; or other object. The cylinder may have a surrounding chamber, a, for the passage of the fluid used for preventing an undue increase of temperature.

D is the compression-cylinder, of any suitable form and arrangement, communicating through ports d d' and a channel, e, with the cylinder A, the channel e having a check-valve, f.

In the cylinder D is a piston, E, having a longitudinal opening, g, provided with a spring check-valve, h, and also with a curved port, i, opening to one side and to the rear of the piston, as shown. The piston E is driven by an eccentric, E', lever E², and connecting-rods from the shaft C, or is otherwise reciprocated in any other suitable manner.

Air is drawn into the cylinder D through an opening, j, and gas is drawn in through an

opening, m, as the piston E moves to the rear, valves k k' closing said openings as the piston moves to the front, at which time the valve h permits the gases to pass to the rear of the piston, said gases being thoroughly mixed as they pass through the opening g. As the piston E again moves to the rear it compresses the gases until the port i is brought opposite the port d, when the mixed gases will flow through said port d, channel e, and port d' into the cylinder A. The cylinder D is shorter and greater in diameter than the cylinder A, the best proportions being about one to two and a half in piston area (more exactly, 1 : 2.749) and three to one in stroke. The connections are such that when the main piston B is at the end of its stroke in either direction the piston E will be in the center of its cylinder, so that as the piston B begins to move forward, the piston E, moving to the rear, will begin to uncover the port d, and the gas will pass under pressure into the cylinder A, the piston E then traveling at its highest speed, while the piston B is at its lowest. By thus reducing the stroke of the compression-piston I am enabled to operate it from an eccentric or tappets and avoid the expensive and more complicated operating parts requisite when a longer stroke is imparted. The ignition-opening n is uncovered by the piston B when the latter has traveled about one-third of its movement, and when the piston E is at the end of its movement, the port e being then closed, the gases exploding, therefore, when at their greatest pressure, which in the engine described will be about two atmospheres.

Any suitable means may be employed for exploding the gases. I prefer, however, a gas-jet arranged at one side of the opening n, but out of direct line therewith, so as not to be extinguished by the issuing jet. By the arrangement described the gases in the cylinder D are cut off from those in the cylinder A at the time of the explosion, so that should the valve f leak no injury will be done to the compression-cylinder. To further guard against injury from too great a pressure, each cylinder is provided with an end opening and a relief-valve, c. On the return movement of the main piston the spent gases are expelled through a port, q, communicating with a channel provided

with a valve, *s*, controlled by a lever, *v*, operated from any moving part of the engine.

To regulate the speed or power of the engine I provide a governing device whereby the sucking or drawing action of the piston *E* is reduced in proportion as the speed of the engine increases. I effect this by circulating the gases from end to end of the cylinder *D* when the speed becomes excessive, thereby reducing the indrawing power of the piston. Different means may be employed for effecting this result. I have shown a circulating-channel, *W*, (dotted lines, Figs. 1 and 2,) with a valve, *Y*, connected to or controlled by a governor, *H*, driven by the engine, the connections being such that the valve *Y* closes the channel until the engine exceeds its normal speed, when, in proportion to such increase, the channel will be opened and a portion of the gases transferred to the front end of the cylinder *D*, thereby reducing the amount of air and gas drawn into the latter and weakening the charge until the speed of the engine is reduced to the desired extent.

As the gases exhausted from the main cylinder of a gas-engine are always at a high temperature, there is ordinarily a great waste of heat, which heat I utilize by conducting said gases to a boiler, radiator, or other apparatus whereby the heat may be advantageously employed. A most effective utilization of the gases in a gas-engine is one whereby the said gases may be made the means of imparting to said gas-engine the initial movements. Thus the heated waste gases from the cylinder *A* may pass through the flues of a steam-boiler, *I*, by which movement is imparted to a steam-engine, *J*, operating upon arms *K K*, swinging freely on the shaft *C*, and carrying pawls *S S*, which engage with a ratchet-wheel, *L*, on the said shaft.

When a cock, *P*, in the pipe *Q* is turned and steam admitted to the engine *J* the shaft *C* will be rotated, and movement will be imparted to the gas-engine until, after the first explosion, it will continue its operations, when the further rotations of the shaft *C* will continue without imparting movement to the steam-engine.

The valve *p* may be provided with a pulley, *M*, for receiving the hand-rope *t*, extending to an elevator-cage or other apparatus at a distance.

I am aware that it has been proposed to use the heated gases generated during the explosion in gas-engines to start the engines, and this I do not claim; and I am also aware that such gases have been injected into water to create a vapor to operate an auxiliary engine connected to the main engine. My invention is distinguished from these by the fact that the hot gases are exhausted directly through the tubes of a boiler without back-pressure, and that as only the heat of the gases is employed no loss of power results from their sudden condensation.

I do not abandon or dedicate to the public any patentable features set forth herein and not hereinafter claimed, but reserve the right to claim the same either in a reissue of any patent that may be granted upon this application or in other applications for Letters Patent that I may make.

I therefore claim—

1. The combination, in a gas-engine, of the main cylinder *A* and an independent compression-cylinder of greater area, and pistons and connections whereby the compression-piston is brought to the end of its stroke after the main piston begins its forward movement, and passages and valve arranged as described, whereby the connection is closed between the two cylinders prior to the explosion, substantially as set forth.

2. In a gas-engine, a compression-cylinder provided with gas and air receiving openings at one end, communicating with the working-cylinder at the other, and provided with a channel for transferring the gases from one side of the piston to the other, whereby their thorough mixture is insured before the charge is expelled, substantially as set forth.

3. The combination of the main and compression cylinders, communicating and igniting ports, and check-valve *f*, all arranged so that the communicating port will be closed by the compression-piston before the igniting-port is uncovered, substantially as set forth.

4. The combination of the main cylinder and piston with a compression-cylinder having air and gas inlets at the forward end, and provided with a piston, *E*, having a passage closed by a check-valve and a port, *i*, extending to the end and side of the piston, substantially as set forth.

5. The compression-cylinder *E*, provided with a circulating passage, a valve in said passage, and connections for operating the valve by the varying speed of the engine, and air and gas inlets, substantially as set forth.

6. The combination of a gas-engine in which the piston is propelled by the explosion of gases, a boiler having tubes through which the exhaust gases from the engine pass freely, and appliances, substantially as described, operated by steam-pressure, and connected to turn the gas-engine shaft without being operated thereby, substantially as set forth.

7. The combination, with the gas-engine and appliances, substantially as described, for storing up a starting-power, of means, substantially as described, for putting said appliances into operation, and connections between the same and an elevator-cage, substantially as set forth.

In testimony whereof I have hereunto set my hand this 3d day of August, A. D. 1882.

CYRUS W. BALDWIN.
